FLARED EXIT PHLEBOTOMY NEEDLE

Edward J. Poitras, Holliston, Mass.

Application January 18, 1951, Serial No. 206,599

6 Claims. (Cl. 128—221)

1

My present invention relates generally to needles and more specifically to hypodermic needles for subcutaneous injections and for piercing puncturable closures in the collection and administration of parenteral, intravenous, and the like surgical fluids, and especially blood. More particularly the invention provides a new and improved needle assembly which is designed to minimize clotting in blood letting and infusing practice, and which is adapted particularly for use with flexible plastic and the like conducting and storing elements permitting the sterile deterioration-free handling of whole blood.

The nature and characteristic features of my invention will be better understood from the following description taken in conjunction with the accompanying drawings which illustrate by way of example preferred embodiments and in which:

Fig. 1 is an elevational view of one needle;

Fig. 2 is a longitudinal sectional view of the same;

Fig. 3 is an expanded sectional view showing the flared end of the needle insert;

Fig. 4 is a view similar to Fig. 3 of an alternative form of the needle;

Fig. 5 is an end elevation, looking at the pointed end of the needle;

Fig. 6 is an elevation looking at the end distal to the point;

Fig. 7 is a view like that of Fig. 1, showing a protective sheath and a fragmentary section of flexible tubing installed at the opposite sides of the manipulating portion;

Fig. 8 is a fragmentary section of a coupling exemplary of prior construction, indicating the flow of the blood at the juncture of the needle and the blood conducting element; and

Fig. 9 is a similar view of a coupling incorporating my novel flared exit needle.

The apparatus employed heretofore in the handling of medical and surgical fluids has been found deficient in one or more of the numerous characteristics or properties required for the sterile collection and infusion and the coagulation-free and degradation-retarding storage of whole blood. In such phlebotomy practice, blood contacting elements of the apparatus must be fashioned of a readily sterilized material which lends itself to a technic by which the blood is kept sealed off from contact with the atmosphere, which is characterized by a non-wettable impermeable surface, and which at least in the case of the blood conducting and storing elements is flexible and collapsible to a degree substantially eliminating liquid gas interface between the blood and

2

the retaining wall. Prior blood letting and infusing needles in particular, incorporating commonly or frequently a female hub coupled to the associated blood conducting tubing through an intermediate adapter, have militated against the air-tight assembly and sterile handling and storage required of such apparatus. More importantly the use of the mentioned adapter and also the uniformly cylindrical bore common to such prior needles have prevented a smooth transition from the lumen of the needle to the tubing, thus giving rise to unwanted clotting of the blood at the coupling.

By the present invention there is provided a novel needle assembly capable of general application but providing particularly the characteristics mentioned as required for best phlebotomy practice. In particular, my novel needle will be seen to have a coupling element adapted to be seized directly to the blood conducting tubing in an air-tight manner and otherwise facilitating the sterile handling of the needle, and also a lumen fashioned specially to minimize clotting of the blood in the region of the coupling.

Referring now to the drawings in greater detail, the needle is indicated generally at A, and comprises a relatively rigid tube or cannula 19, preferably of stainless steel, which has a smooth and generally uniform lumen or bore 11 extending uninterruptedly throughout its entire length to promote laminar flow of the blood and to facilitate cleaning. The cannula may be manufactured in any desired size, as for example 15 gauge, a size causing minimum physiologic disturbance to a donor and thus found desirable in phlebotomy, or it may be for further example 19 gauge, which is a size permitting a desired rate of flow for infusion purposes. The cannula 19 will be cut or ground obliquely at one end to form a piercing or puncturing point 12 in known manner.

As hereinbefore mentioned desired anti-coagulant and clot-free handling of blood as for example in phlebotomy practice has been hampered heretofore by disturbance of the flow of the blood at the coupling of the blood-letting needle with the blood conducting tube. Such clot-forming disturbance or interference with smooth laminar flow is understood to result from the sharp break or more particularly the annular shoulder in the wall of the blood passage and the substantial passage enlargement or cavity formed at the coupling by the overlapping of the associated end of the blood conducting tube and the right-angled exit end universally characterizing prior needle assemblies, all as indicated at B in Fig. 8. It

will be understood that the flat-faced end wall and the flow eddying cavity formed adjacent thereto are characteristic of prior structures irrespective of whether the coupling is direct to the needle or through an adapter as mentioned. Thus Fig. 8 may be regarded as representative of the coupling of a needle proper, or of either end of such adapter with the associated blood conducting element, in the prior practice.

The needle of the present invention is novelly constructed and arranged at the end remote from the piercing tip to minimize and substantially preclude the described interference with the laminar flow of the blood, irrespective of the direction of such flow. More particularly, the needle bore is formed with a gently flaring, conical enlargement, as indicated generally at C in Figs. 3 and 4. Such conical flare is seen to be convergent with the oppositely tapering coupling hub 22 (to be described hereinafter), and to merge therewith at the end of the needle to define a relatively thin-walled, annular rim, which is rounded, as shown, to eliminate altogether the cavity-forming right-angular flat-faced construction heretofore mentioned. I have found a flare of about 10° taper and proportioned and arranged to reduce the needle wall thickness at the rim to about 0.020" to be eminently satisfactory in use. As indicated particularly in Fig. 9, the described needle bore flare smoothly shapes and guides the flow of the blood into the sometimes larger or different diameter blood conducting element, and the associated end of such conductor, expanded as shown over the mentioned needle coupling hub, desirably hugs and contracts about the described rounded end wall of the needle so as substantially to eliminate the cavity mentioned as previously characterizing the region of the coupling. Thus the probability of clotting at the coupling end of the needle commonly experienced heretofore is substantially eliminated by the flared construction described.

Referring now more particularly to Figs. 1, 2 and 7, a coupling and manipulating portion or element 20 of the needle is rigidly and permanently mounted on the cannula at the end distal to the point 12 in any convenient manner, as by sweating or fusing. Such element may be of metal, which may be the same as or similar to that of the cannula 10, or a more easily machinable metal or alloy such as a brass with chrome plating. In the preferred form, however, it has a plastic composition, as for example nylon, which lends itself to the desired hermetically sealed, firm-gripping engagement with the associated blood conducting tube. It is here noted also that a coupling element fashioned of a slightly compressible plastic, such as nylon, effects an excellent seal with the relatively incompressible socket of other units such as a syringe tube, sharpening fixture, and washing device, to which the needle may be coupled.

This cannula surrounding element 20 as shown comprises an intermediate manipulating body 21 of four-sided or other outside contour, preferably non-round, merging oppositely into aligned tapered conical coupling hubs 22, 23, which are dimensioned to fit within and seize to the open end of flexible tubing *t* of standard proportions, as indicated in Fig. 7. Hub 22, at the end remote from the needle point and over which the tubing or other resilient tubular element is fitted when the apparatus is assembled for use is somewhat longer and of a flatter taper than hub 23, as shown, to provide additional tube anchoring sur-

face and especially secure inter-gripping action. The distinctive functions of the respective hubs in this regard will more fully appear hereinafter.

Where the coupling and manipulating element 5 20 is formed as preferred of a plastic such as nylon molded directly about the cannula 10, a more secure interconnection of the two members is obtained by fashioning the element 20 with a portion overlying the end of the cannula 10. In such case this molded element 20 is itself also formed with an internal flare 24, Figs. 2 and 3, substantially continuous with and also exactly conformant to cannula flare 13. Thus in the preferred embodiment of Fig. 3 the joint between the 15 cannula 10 and manipulating element 20 is internal at the exit or tube connecting end of the needle.

Where alternatively a metallic coupling element 20a is employed, Fig. 4, manufacturing convenience is served by terminating it flush with the cannula 10a at the exit end of the needle. In such instance the flared portion of the cannula is extended as shown at 13a to maintain the desired lumen surface configuration and needle wall 25 thickness. It will be apparent that with the embodiment of Fig. 4 as with the preferred form of Fig. 3 the tube-gripping surfaces of the coupling element are uninterrupted, the joint between element 20a and cannula 10a being located in the like reduced and rounded end wall. The needles of Figs. 3 and 4 may be identical in other constructional respects, providing commonly and importantly the lumen flare already described.

To maintain the needle in a sterile, protected 35 condition ready for use the cannula is enclosed in a sheath 40, shown in Fig. 7, placed over the cannula and seized to the shorter hub 23. The relatively short length and steep taper of hub 23 makes for easier removal of the sheath. It 40 is noted that an entire blood handling apparatus may be kept in a sterile condition by sealing the free ends of the blood conducting tubes with my novel needle, in the manner just described. While the described double hub and coupling portion 45 20 of the needle performs satisfactorily as to tube-gripping and sealing action when of a metallic construction, as in Fig. 4, for best results, more particularly a still firmer, hermetically sealed coupling with the flexible plastic tubing *t*, it is 50 fashioned of nylon or a like plastic material, as recited for the preferred embodiment of Fig. 3.

Where the needle is to form part of apparatus 55 designed to prevent or delay coagulation and degradation of the blood, the cannula desirably is treated with a medium which furnishes with respect to blood a non-wetting bore lining or film to prevent clotting of the blood passing therethrough. For this purpose a substantially monomolecular anti-coagulant film is applied from a dilute (0.1 to 1%) aqueous dispersion of such substance as exemplified by either dicocodimethyl ammonium chloride or octadecyl primary amine. Alternatively, the cannula itself may be fashioned 60 of nylon or such other synthetic resin as possesses the desired toughness while presenting sterilizable chemically clean, inert, and non-wettable surfaces to the blood.

Upon assembly with the sheathing and/or tubing or other tubular connection the needle 70 and accompanying apparatus are placed in condition for use by sterilizing by any technically acceptable method, as for example by subjecting it to a temperature of not less than 120° C. for a continuous period of at least thirty 75 minutes.

My novel needle is shown in the ready-for-use condition in Fig. 7. It will be obvious that it may be readily manipulated by grasping element 20 at the gripping portion 21. The needle is placed in use merely by removing the protective sheath 40, as facilitated by the shorter and steeper conical hub 23 as contrasted with the other hub 22 and the retention of its grip with the tubing, and applying the needle to the donor or recipient as required. The smooth and uninterrupted cannula bore of lumen promotes the desired laminar flow of the blood at a rate determined by the needle gauge. The longer and flatter conical hub 22 insures a secure, airtight coupling with the associated tubing section, adapted to be maintained under all conditions of use. And as importantly and novelly provided by the present invention the lumen exit flare 13, 24 promotes and preserves a smooth transition from the needle to such tubing section, thereby substantially reducing and minimizing the likelihood of coagulation or clotting at the coupling.

From the foregoing it will be readily appreciated that by my present invention the sterile and deterioration-free collection, storage and administration of parenteral fluids, and particularly of whole blood, is made possible with a needle assembly adapted particularly for use with apparatus having blood protecting and preserving characteristics, but having general utility in phlebotomy, blood administering and other practice where a hypodermic needle is required.

My invention is not limited to the exemplary embodiments herein illustrated or described, and I set forth its scope in my following claims.

I claim:

1. A new and improved anti-coagulant hypodermic needle adapted directly and sealingly to be coupled to a blood conducting member, said needle comprising a rigid cannula having opposite pointed and non-pointed ends, said cannula defining and extending continuously over substantially the full length of the needle, an elongate coupling and manipulating element directly concentrically surrounding an intermediate portion of the cannula and the adjoining non-pointed end thereof, said cannula having a laminar flow promoting lumen of generally uniform diameter but formed at the non-pointed end with a gently flaring enlargement of the opening reducing the wall thickness of the needle at said end and also guiding

and controlling the flow of the blood for minimum disturbance in the region of the coupling whereby clotting of the blood thereat is substantially eliminated.

5 2. A needle according to claim 1 wherein the lumen wall carries an anti-coagulant film.

3. A new and improved anti-coagulant hypodermic needle comprising a coupling and manipulating element including a sleeve formed at one end with a tapered coupling hub adapted for seizing reception in a flexible tubular blood-conducting element, and surrounded thereby a relatively rigid cannula pointed at the end remote from said hub and formed with a lumen of generally uniform diameter but flaring at the coupling end thereof, whereby a smooth transition from said cannula to such blood-conducting element is effected and clot-forming disturbance of the flow of the blood in the region of the coupling is minimized.

10 4. A needle according to claim 3, wherein the coupling and manipulating element is of a synthetic resin molded onto the cannula and formed with a portion extending beyond the coupling end of the cannula and having a lumen-forming inner wall substantially continuous with and tapering conformant to said flared exit end thereof.

5 5. A needle according to claim 3, wherein the coupling and manipulating element is of metallic construction, and is terminated flush with the cannula at the coupling end of the said needle.

30 6. A coupling according to claim 3, wherein the hub and lumen converge terminally to form a relatively thin walled rounded rim about which the connective element contracts to present a blood-conducting passage substantially continuous with said lumen.

EDWARD J. POITRAS.
